UNITED STATES PATENT OFFICE.

ROLLS PERCIVAL LINK, OF LONDON, ENGLAND.

PRESS FOR PRINTING, EMBOSSED, OR THE LIKE.

Application filed March 17, 1926, Serial No. 95,370, and in Great Britain December 18, 1925.

This invention relates to presses for printing, embossing or the like, and provides an improved press more especially adapted for embossing or imprinting selected designs, 5 letters or other characters in or on suitable materials, for example, show or advertisement cards, price tickets, book covers and like articles.

According to this invention, the improved 10 press comprises a base plate provided with a suitable surface or lower ram plate on which a form, printing bed plate or the like can slide, and standards or uprights forming guideways for a movable or upper ram 15 plate fitted to the guideways in such a manner that any rocking or tilting movement of the upper ram plate is precluded. Bearings are arranged in the standards for a cam shaft provided with a central handle and 20 cams at each side of this handle whereby pressure can be applied to the movable or upper ram plate, these shafts also carrying plates having cam grooves therein providing tracks for rollers carried by the movable or upper 25 ram plate, so that the said movable or upper ram plate can be raised thereby when the shaft is rotated in the appropriate direction. Means are also provided to determine the limit of downward movement of the 30 said upper ram plate.

In the accompanying drawing, which shows how the said invention can be conveniently carried into practice.

Figure 1 is a side view of the improved 35 press with the movable or upper ram plate in the raised position.

Figure 2 is a front view of the press with the movable or upper ram plate in its lowermost position.

Figure 3 shows a section on the line 3—3 of Figure 2.

As shown in this drawing, the improved press comprises a base plate *a* provided with a surface *b* serving as a stationary or lower 45 ram plate on which a form *c*, printing bed plate or the like can be supported, the said form being slidable on the lower ram plate so that it can be set in a position below a movable or upper ram plate *d* or drawn out 50 from below the latter, as required. The upper ram plate is guided in guideways provided by machined faces on standards or uprights *e* arranged laterally to the lower ram plate. The standards or uprights can conveniently be made rectangular in horizontal

section as shown in Figure 3, with machined faces on the exterior side thereof, and the upper ram plate can be provided with lugs or arms *f*, of substantial dimensions in the vertical direction, forming rectangular 60 grooves at the opposite ends of the movable ram plate providing surfaces which are slideable along three of the faces of each standard or upright, so that any rocking or tilting 65 movement of the upper ram plate is precluded and this plate is constrained to remain parallel to the fixed or lower ram plate as it is moved towards and away from the latter.

In the upper parts of the standards or uprights, bearings are provided for a shaft *g* having a handle *h*, by means of which it can be rocked, keyed thereto in a central position between the bearings. On each side of this handle and between the bearings of the shaft, cams *i* are formed on the shaft to thrust against suitable surfaces *j* arranged for this purpose on the movable or upper ram plate. The outer ends of the shaft which project through the bearings carry 70 plates *k* in which cam grooves *l* are formed to receive rollers *m* mounted on pins *n* projecting from central parts of end or strap plates *o* attached to the outer ends of the lugs or arms *f* of the upper ram plate. The 75 said strap plates *o* are arranged to slide on guide surfaces provided on standards or uprights *e* and thus assist in preventing endwise or rocking movements of the upper ram plate. The plates *k* in which the cam grooves 80 *l* are formed can then be arranged in contact with the strap plates so as to prevent axial movement of the shaft in its bearings. 85 With this arrangement, when the shaft *g* is turned to cause the cams to press down 90 the upper ram plate, the effects of torsional strain of the shaft are avoided and the upper ram plate, by means of the central arrangement of the operating handle, can be actuated so as to apply an equal pressure from 95 end to end on an article or material inserted between the upper and lower ram plates.

The cam grooves *l* above mentioned are employed for lifting the upper ram plate and act through the rollers *m* on the strap plates *o* bolted to the ends of the lugs or arms *f*. These cam grooves can be made of such a length that they limit the angle through which the handle can be turned, 100 and thus determine the extreme positions to 110

which the upper ram plate can be moved. The contour of the grooves *l* and the width thereof compared to the diameter of the rollers *n* are however preferably such that the weight of the ram is allowed to assist in the printing, embossing or pressing operation.

When it is desired to prevent the upper ram plate from moving downwardly to the 10 lowermost position allowed by the positions of the ends of the cam grooves *l*, the strap plates *o* are formed with inclined lower edges, and stop plates *p* with inclined upper edges are slidably mounted below the said 15 strap plates. By adjusting these stop plates in their slides, an accurate adjustment of the lowermost position of the upper ram plate can be ensured, as may be necessary or desirable to limit the ultimate compressive 20 effort which can be exerted by the upper ram plate on material placed beneath it. As shown in Figure 1 the stop plates *p* are held against the standards or uprights by bolts *q* passing through slots *r* in the plate and are 25 adjustable in the direction of their length by adjustment or feed screws *s* having flanges *t* thereon which at one side projects into a groove in the stop plate, the feed screw *s* being carried in a tapped hole in the standard. 30 The lower edge of the stop plate *p* is supported on a guide surface provided on the standard *e* so that any downward thrust on the stop plate does not exert any shearing effort on the bolts *q*. The feed screws or the 35 stop plates can be marked with scales or graduation marks to indicate their positions of adjustment.

I claim:

1. An embossing press comprising a lower 40 ram plate, an upper ram plate, standards on the lower ram plate serving as guideways for the upper ram plate, a shaft mounted to rock in bearings in the standards, an operating handle arranged at a central part of the shaft, cams on the shaft between the said handle and the shaft bearings whereby the said upper ram plate can be depressed, grooved plates carried by the shaft, and means carried by the upper ram plate and

working in the grooves of said plates to limit 50 the movement of the upper ram plate.

2. An embossing press comprising a lower ram plate, an upper ram plate, standards on the lower ram plate, arms on the said upper ram plate movable along guide surfaces provided on the standards, a shaft mounted to rock in bearings in the standards, an operating handle arranged at a central part of the shaft, and cams on the shaft between the said handle and the shaft bearings whereby the said upper ram plate can be depressed.

3. An embossing press comprising a lower ram plate, standards of rectangular cross section on the said lower ram plate, an upper ram plate slidable along guideways provided on the outer faces of the said standards, arms on the said upper ram plate respectively extending on opposite sides of the standards, strap plates at the outer ends of said arms 65 arranged to slide on the said standards, a shaft mounted to rock in bearings in the standards, an operating handle arranged at a central part of the shaft, and cams on the shaft between the said handle and the shaft 70 bearings.

4. An embossing press comprising a lower ram plate, an upper ram plate, standards on the lower ram plate serving as guides for the upper ram plate, a shaft mounted to rock 80 in bearings in the standards, an operating handle arranged at a central part of the shaft, cams on the shaft whereby the said upper ram plate can be depressed, rollers carried on the upper ram plate, and plates carried by the shaft and having cam grooves therein forming tracks for the rollers whereby the said upper ram plate can be raised.

5. An embossing press comprising a lower ram plate, an upper ram plate, standards 90 on the lower ram plate serving as guides for the upper ram plate, a shaft mounted to rock in bearings in the standards, cams on the shaft whereby the upper ram plate can be depressed, and adjustable stop plates for limiting the downward movement of the said upper ram plate.
